(57) **CLAIM**

The ornamental design for a portable curtain kit and suction cup therefor, as shown and described.

DESCRIPTION

FIG. 1 is a perspective view of a curtain and suction cups of a portable curtain kit in a disassembled state.

FIG. 2 is a right side view of the portable curtain kit thereof, in a disassembled state.

FIG. 3 is a front view of the portable curtain kit thereof, in a disassembled state.

FIG. 4 is a left side view of the portable curtain kit thereof, in a disassembled state.

FIG. 5 is a back view of the portable curtain kit thereof, in a disassembled state.

FIG. 6 is a top view of the portable curtain kit thereof, in a disassembled state.

FIG. 7 is a bottom view of the portable curtain kit thereof, in a disassembled state.

FIG. 8 is a back view of the curtain of the portable curtain kit thereof.

FIG. 9 is a front view of the curtain of the portable curtain kit thereof.

FIG. 10 is a back view of the portable curtain kit thereof, in an assembled state.

FIG. 11 is a front view of the portable curtain kit thereof, in an assembled state.

FIG. 12 is an enlarged fragmentary left back perspective view of the portable curtain kit thereof, according to detail 12, 13 shown in FIG. 11, in an assembled state.

FIG. 13 is an enlarged fragmentary side view of the portable curtain kit thereof, according to detail 12, 13 shown in FIG. 11, in an assembled state.

FIG. 14 is a back view of a curtain of the portable curtain kit, according to a second embodiment, the front view being the same as FIG. 9.

FIG. 15 is a back view of the portable curtain kit thereof, in an assembled state, the front view being the same as FIG. 11.

(Continued)

FIG. 16 is an enlarged fragmentary left back perspective view of the portable curtain kit thereof, according to detail 16, 17 shown in FIG. 15, in an assembled state.

FIG. 17 is an enlarged fragmentary side view of the portable curtain kit thereof, according to detail 16, 17 shown in FIG. 15, in an assembled state.

FIG. 18 is a bottom front perspective view of the suction cup component of embodiments 1 and 2, in a released state with the remaining components removed.

FIG. 19 is a bottom front perspective view of the suction cup component thereof, in an engaged state with the remaining components removed.

FIG. 20 is a top view of the suction cup component thereof.

FIG. 21 is a right side view of the suction cup component thereof.

FIG. 22 is a bottom view of the suction cup component thereof, with the remaining components removed.

FIG. 23 is a left side view of the suction cup component thereof, with the remaining components removed.

FIG. 24 is a front view of the suction cup component thereof, with the remaining components removed; and,

FIG. 25 is a back view of the suction cup component thereof, with the remaining components removed.

The break lines shown in the figures symbolize breaks in the length or width of the article in which the claimed design is embodied. The appearance of any portion of the article between the break lines form no part of the claimed design. Portions shown in dashed lines do not form part of the claimed design. Environment is shown in dot-dash lines and do not form part of the claimed design.
